UNITED STATES PATENT OFFICE.

PERLEY R. GLASS, OF BOSTON, MASSACHUSETTS, ASSIGNOR, BY MESNE ASSIGNMENTS, TO CHARLES WHITTEMORE, OF NEWTON, MASSACHUSETTS.

EYELETING-MACHINE.

SPECIFICATION forming part of Letters Patent No. 628,309, dated July 4, 1899.

Application filed March 31, 1897. Serial No. 630,115. (No model.)

To all whom it may concern:

Be it known that I, PERLEY R. GLASS, of Boston, county of Suffolk, and State of Massachusetts, have invented an Improvement in 5 Eyeleting-Machines, of which the following description, in connection with the accompanying drawings, is a specification, like letters on the drawings representing like parts.

The present invention relates to a setting- 10 machine for setting eyelets, rivets, and the like, and is shown as embodied in a machine having the same generic features of construction and arrangement as those shown in prior applications filed by me on May 20, 1896, Serial 15 No. 592,364, and October 2, 1896, Serial No. 607,653, and the application filed jointly by me and Walter L. Whittemore on December 18, 1896, Serial No. 616,220.

The invention is mainly embodied in an automatic gage for the stock, the functions of which will be hereinafter described, and in means whereby one or more holes not intended for the reception of eyelets or the like may be punched by devices which are normally 20 inoperative, but adapted to coöperate, at the desire of the attendant or at a predetermined period, with the mechanism which performs the setting operations, so that the stock to be operated upon—such as a shoe-upper, for example—may have one or more eyelets or the like set therein and one or more holes merely punched without increasing the number of movements made by the main instrumentalities of the machine. Furthermore, the eyelet feed-chute, which is adapted to present the eyelets one by one to the eyelet-setting devices, is herein shown as duplicated, or “made in multiple,” so to speak, there being two or more separate eyelet-chutes mounted on said 25 frame, each having a separate hopper adapted to contain eyelets, one hopper, for example, containing eyelets having tops of one color and another hopper containing eyelets having tops of another color, so that when the same machine is to be used on different classes of work where different-colored eyelets are to be employed it is necessary only to shift the position of the raceways so that the end of one raceway will be out of the path of the 30 eyelet-setting devices in the operation of the machine and the end of another raceway in

said path, means being provided in accordance with the invention for thus shifting the position of the raceway by a simple actuating device.

55

In eyeleting and preparing shoe-uppers it is customary to “spread” the eyelets or set certain of them farther than others from the edge of the upper, it being customary to set most of said eyelets at substantially the same 60 distance from the said edge, while the last two or three eyelets in the line as it approaches the point where the upper is connected to the vamp are usually set at a somewhat greater distance from the edge, the distance increasing 65 toward the point of connection with the vamp, so that the lower eyelets are practically set along a curved line. It is obviously necessary, therefore, in eyeleting shoe-uppers to properly gage the stock so that the punch 70 and eyelet-setting devices may bear the proper relation to the edge of the stock to set the eyelets as above described, and the present invention is partly embodied in an improved gage for the stock, the position of which gage 75 is automatically shifted during the operation of the machine at the proper time in the operation thereof. In eyeleting uppers, however, it is obvious that the two uppers of each pair must be respectively run through the machine 80 in opposite directions. In other words, inasmuch as the tops of the eyelets must always be at the outside of the stock it is obviously necessary that one upper of each pair should be presented to the machine lower-end first and 85 the other upper of the same pair presented to the machine upper end first, while the spread of the eyelets always occurs at the same end of the uppers—that is to say, the lower end thereof or end adjacent to the shoe-vamp. It 90 is essential, therefore, that the gage which determines the spread of the eyelets should operate to change the position of the stock, in one instance at the beginning of the operation of the machine and in the other instance 95 at the end thereof, and that it should work in opposite directions, since it is obvious that if the lower end of the upper is first presented to the machine the gage should be first in a position to set the eyelet farthest from the 100 edge at the initial operation thereof and then nearer to the edge at each succeeding opera-

tion until the normal position is reached, while if the top of the upper is first presented to the machine it is obviously essential that the gage should remain stationary until the last of the main series of eyelets is inserted and then moved step by step to change the relation of the stock to the devices operating thereon and produce the spread of the remaining eyelets. In accordance with the present invention the said gage is arranged to remain stationary during the first part of the operation of the machine upon an upper which is started from the top, and after a certain number of eyelets have been inserted and it is desired to spread the remainder or vary the position thereof with relation to the edge of the stock the gage is thrown into operation by means of a device under the control of the attendant and is then moved one step at each operation of the punch and eyelet-setting devices, so as to change the position of the stock after each of such operations. In other words, after the lever is operated the gage recedes step by step from the punch and eyelet-sets, so that they operate farther and farther from the edge of the stock, whereby each succeeding eyelet is set somewhat farther from the margin than the preceding eyelet. After the last eyelet is inserted the machine is stopped and the other upper of the pair is placed in position to be operated upon, the gage then being in its most remote position with relation to the punch and eyelet-setting devices, so that the first eyelet inserted is at the maximum distance from the edge to correspond with the position of the last eyelet inserted in the previous operation of the machine. The gage then automatically approaches the position of the punch and eyelet-setting devices until three or more eyelets have been inserted, after which it remains stationary during the remainder of the operation and during the first part of the succeeding operation on the next upper until again brought into operation by the attendant.

In conjunction with the devices above described the machine embodying the present invention is provided with means whereby two or more holes in which eyelets are not intended to be inserted may be punched at a single movement of the machine, this being accomplished by providing the machine with a supplemental punch or gang of punches which are normally inoperative, but adapted to coöperate with the main punch at the will of the attendant, so that when, for example, a number of eyelets have been inserted by the normal operation of the machine the attendant can cause the supplemental punch to operate in conjunction with the main punch to make a hole or series of holes in the stock at the same time that the main punch makes its hole, the machine usually being stopped after the eyelet-setting devices have operated to insert an eyelet in the hole punched by the main punch, the holes formed by the supple-

mental punch or gang of punches being left without eyelets, it being practicable, moreover, and in some cases desirable to also leave the last hole made by the main punch uneyeleted, as will be described. This feature of the invention is of importance not only on account of the saving of time in the operation of preparing a single upper, but also because of the fact that it is frequently desirable to make holes for the lacing-studs which are to be subsequently inserted, which holes differ in size from those used for the insertion of the eyelets, while it is also desirable in some cases to space the lacing-studs differently from the spacing of the eyelets, this being obviously easily accomplished by having the supplemental punch or punches of the desired size and arranged any desired distance apart. It is obvious that in some cases a single supplemental punch might be desirable and useful—as, for example, if it became desirable or necessary to make a row of holes alternately eyeleted and non-eyeleted; but the main advantage is that a plurality of holes may be punched at one operation, and the machine is herein shown as provided with a gang of supplemental punches, which will be mainly hereinafter referred to, for convenience, as the "gang-punch."

Figure 1 is a side elevation of a machine embodying the present invention; Fig. 2, a sectional detail on line x^2 of Fig. 1; Fig. 3, a top plan view of the main portions of the machine, the eyelet-chute being broken away to better illustrate the features of the present invention; Fig. 4, a detail showing the automatic gage which forms a feature of the invention, a shoe-upper which is to be operated upon being shown in connection therewith and the said gage being in its initial position, ready to guide the stock for spreading the eyelets at the lower end of the upper. Fig. 5 is a similar view showing the gage in the position which it reaches when the machine is stopped after the first upper is completely eyeleted and the corresponding upper is inserted ready to be operated upon; Fig. 6, a top plan view of the multiple eyelet-chute, which forms a feature of the invention; Fig. 7, a section on line x^7 of Fig. 6, showing the means for shifting the eyelet-chute; Fig. 8, a side elevation of the machine looked at from the side opposite that shown in Fig. 1; Fig. 9, a front elevation of a portion of the machine, showing the main and supplemental punches; and Fig. 10 a detail to be hereinafter referred to.

The main operating parts of the machine are shown as mounted in a frame A and comprise the main punch a, operated by the punch-lever a², pivoted at a³ upon the side of the said frame, and the eyelet-setting devices, one of which is mounted in an overhanging arm A² of the frame and the other upon a reciprocating rod c², operated by the lever c³, the said punch and eyelet-setting devices being operated by the main shaft having the

eccentric disk B thereon, substantially as shown and described in the prior applications above referred to. In conjunction with said punch and eyelet-setting devices the machine is provided with the stock-feeding device, comprising the slide d , adapted to reciprocate along the work support or table T through the operation of the lever D, and having the coöperating feed or gripper member d^3 normally pressed downward toward said feed-slide d , but adapted to be lifted therefrom during the movement thereof in one direction by the device which operates the lower set, substantially as described in said prior applications, the gripper member being mounted on a vertically-movable guide-rod d^3 , supported by the lever D, and a bracket or extension d^4 from the feed-slide d .

The feeding device e for presenting the eyelets to the eyelet-setting device is shown as a reciprocating support or frame mounted upon guide-rods e^2 and connected by means of a pitman e^3 with a wrist-pin B^2 on the disk B aforesaid, so as to have a reciprocating movement. The said feeding device or "chute-carrier," as it may be called, is herein shown as provided with two or more separate raceways or chutes e^4 , each of which is adapted to receive the articles to be set, such as eyelets, from an independent hopper e^5 , so that when it is desired to use the same machine for different kinds of work in which different-colored eyelets are required it is not necessary to change the eyelet chute and hopper or to take out the contents of the hopper and refill the same, means being provided in accordance with the present invention for shifting the position of the raceways so that any one of the same can be brought to the proper position to present its eyelets to the eyelet-setting devices while the other is out of the way of said eyelet-setting devices, and consequently inoperative. To this end the said raceways e^4 (of which but two are shown, it being obvious that three or more might equally well be utilized) are mounted upon or formed in a supplemental support or plate e^6 , having a tongue or projection e^7 , supported in a bearing e^8 in a lug or supporting portion e^9 of the reciprocating frame e and secured thereon, as by a nut e^{10} . It is obvious, therefore, that by turning the said plate e^6 upon the projection e^7 in the bearing e^8 the raceways and hoppers will be shifted in position, so that the lower end of either raceway may be brought into proper position to coöperate with the setting devices in the feed movement of the chute-carrier and present its eyelets to said setting devices in any suitable or usual way while the other chute is practically inoperative. It is obvious that the said multiple chutes and hoppers may be arranged to be shifted in any suitable way, the movable support therefor being shown in this instance as provided with a latch e^{12} , having a handle e^{13} and spring e^{14} , the said latch coöperating with shoulders or slots e^{15} in the

edge of the supporting-plate e^9 , so that the chutes may be readily shifted in position and locked.

The hoppers e^5 are shown as provided with agitating devices e^{50} , which may be of any suitable or usual construction, for the purpose of agitating the eyelets in the hoppers, so that they will be properly presented to suitable openings which lead to the chutes, the said devices being herein shown as consisting of frames or disks having brushes attached to the periphery thereof, the said disks being mounted on spindles e^{51} , one of the said spindles being provided with a crank-arm e^{52} , connected by a link or rod e^{53} with the frame A of the machine, so that the said spindle will be turned during and in response to the reciprocating movement of the feed-chute, the brushes being thus oscillated along the bottom thereof. To properly actuate all of the agitating devices, those in one of the hoppers are shown as connected to those in the other hopper by means of a gear, each of the spindles e^{51} being shown as provided with a spur-gear e^{54} , the said gears intermeshing, so that the proper movement of the agitating devices in each of the hoppers is insured.

The punch a and the punch-lever a^2 are shown as constructed, operated, and arranged substantially as described in the prior applications above referred to. In the normal operation of the machine the said punch operates upon the stock, which is then fed forward by the stock-feeding device to have an eyelet inserted by the eyelet-setting devices in the hole previously punched, this operation being repeated until the upper is finished, the setting devices, however, being sometimes rendered inoperative during part of the process, so that a certain number of the holes are punched without having the eyelets set therein, this being accomplished, for example, by the shifting-cam e^{20} , which coöperates with the yoke e^{21} upon the pitman e^3 and is adapted to coöperate by means of a projection e^{22} with an elbow-lever e^{23} to shift the point of connection between the pitman e^3 and the eyelet-feeding device e , substantially as shown and described in the Glass and Whittemore application above referred to.

In order to facilitate the punching of the holes in which the eyelets are not to be set and at the same time to provide means, if necessary, for making the said holes of a size different from that of the holes in which the eyelets are set or at different spaces apart, the machine is provided, in accordance with the present invention, with a supplemental punch or gang of punches f , shown as mounted on a supplemental punch-lever f^2 , which is normally inoperative, but provided with actuating mechanism adapted to be connected therewith, whereby it is caused to operate in addition to the main punch a , so that at any given operation of said main punch a the punch or gang of punches f and the punch a may all be caused to operate upon the stock.

For convenience the supplemental punches, of which three are herein shown, will be hereinafter referred to as the "gang-punch" and the lever f^2 as the "gang-punch" lever.

- 5 The gang-punch f may be utilized in several different ways, as may be explained with reference to the shoe-uppers U, as shown in Figs. 4 and 5. In each instance the said uppers must be fed through the machine in the 10 direction of the arrow, Fig. 4 showing the right-hand upper of a shoe, said upper having had the main portion of the openings punched therein and about to have the last openings at the lower end thereof punched 15 and eyeleted, while in Fig. 5 the left-hand upper is shown at the beginning of the operation of the machine thereon with an opening about to be punched and eyeleted at its lower end, to be followed in the operation 20 of the machine by the remaining openings. Since the punch is intended to make the openings which are not to be eyeleted, the said gang-punch must usually operate when the top of the upper is in a position to have 25 the openings punched therein by the said punch, so that with the right-hand upper, Fig. 4, the gang-punch should operate at the first operation of the machine upon the upper, while with the left-hand upper the gang- 30 punch should be the last to operate thereon.
- In some classes of work, as has been stated, the lacing-studs require an opening of different size from that required by the eyelets, while in other cases all of the openings may 35 be of the same size, and in still other cases it may be desirable to have an eyeleted opening at the top of each upper, with openings of different size between the same and the main line of eyeleted openings for the insertion of 40 lacing-studs. Taking the first class of work and operating upon the right-hand upper, the attendant will first place the stock in the machine in a position to be operated upon by the gang-punch, but not by the main punch, 45 and will cause the machine to make one revolution, at the same time throwing the gang-punch into operation, so that the three upper holes are punched for the reception of the studs. He will then move the stock forward 50 until it is in the proper position to have the next hole made by the main punch a and start the machine, this time allowing it to run and automatically punch and eyelet the remainder of the holes. With the left-hand 55 upper he will place the stock in the proper position without throwing in the gang-punch and start the machine, which will punch and eyelet the lower set of holes, and after the said holes are punched and eyeleted the attendant can, without stopping the machine, throw in the gang-punch, which will descend with the main punch at the last operation thereof, so that all the remaining holes are punched at one operation, the stock then being fed so that an eyelet is inserted in the 60 hole made by the main punch, after which the machine is stopped. Where the holes are

to be all of the same size, the operation is substantially the same, except that the main punch may be caused to make one of the non-eyeleted openings, the right-hand upper in this instance being placed in such a position as to be punched at the first operation not only by the gang-punch but by the main punch. With the left-hand upper the last 70 operation of the machine is that of punching the last opening made by the main punch, together with the line of openings made by the gang-punch, the eyelet-setting devices being rendered inoperative in this instance during 75 the last movement of the machine, so that the hole made by the main punch cannot receive an eyelet therein. Where the holes made by the gang-punch are to be of a different size from those made by the main punch 80 while an eyelet is to be inserted in the first hole at the top of each upper, the operation upon the left-hand upper is substantially the same as before, except that the machine is allowed to set an eyelet in the hole made by 85 the main punch after the main punch and gang-punch have first operated, and it is then stopped to have the upper moved along prior to the normal operation of setting the lower line of eyelets. With the right-hand upper 90 the machine is stopped after the main and gang punches have operated together and an eyelet has been set in the opening made by the main punch, after which the stock is manually moved to a position to have the top 95 opening made by the main punch and an eyelet set therein.

To operate the gang-punch f in the manner and for the purpose above described, the lever f^2 is shown as mounted parallel to and coaxially with the main-punch lever a^2 , which in this instance constitutes the actuating mechanism for the said gang-punch, both of said levers being herein shown as having a bearing upon a spindle supported between the 100 side of the main frame A and an upright arm or bracket-piece A^3 formed at the side of the frame and also being adapted to afford a bearing or support for the elbow-lever e^2 , which has been hereinbefore referred to in conjunction with the means for shifting the point of connection between the eyelet-feed chute and its operating mechanism and which is also utilized in conjunction with the gang-punch, 105 as has been described.

As has been stated, the main-punch lever a^2 is caused to rock on its pivot at each rotation of the main shaft, it being obvious, therefore, that if the gang-punch lever f^2 is provided with means whereby it may be temporarily connected with said lever a^2 the said lever a^2 will serve as actuating means whereby the lever f^2 will also be rocked upon its pivot, so that the punches a and f , which, as shown in Fig. 3, are arranged in a line along 110 the work-support or feeding-table, may be all moved simultaneously toward said feed-table to punch a line of holes in the stock lying thereon. To thus operate the lever f^2 , the 115

said lever is shown as provided with a movable projection or pin f^3 , mounted in a guide-way f^4 and adapted, as shown in Fig. 2, to be moved into the path of the lever a^2 to be engaged and moved thereby, the said lever a^2 being shown as provided with a shoulder a^4 , adapted to engage said pin f^3 when it is moved into the position shown, the said pin, however, normally being withheld from the path of the said shoulder, as by a spring f^5 coöperating with a shoulder or enlargement f^6 . When, therefore, the parts are in their normal position, the main punch and the other instrumentalities will operate in the usual way without any corresponding operation of the punch-lever f^2 , which is normally held up away from the feed-table by the spring f^1 . (See Fig. 1.) To cause such operation of the lever f^2 , means are provided for throwing the pin f^3 into engagement with the shoulder a^4 , and for this purpose the machine is shown as provided with an arm or lever g , adapted to engage the pin f^3 and to press the same to the left, Fig. 2, or, in other words, to the position shown therein, and the said arm g may consist of one arm of an elbow-lever having a bearing g^2 , formed in the bracket portion A^3 of the frame A , and having another arm g^3 connected therewith and underlying the elbow-lever e^2 , which is intended to be operated, as indicated, by a treadle. (Not shown.) When, therefore, it is desired to cause the gang-punch to operate, the lever e^2 may be depressed, and thus cause the arm g or "elbow" g^3 , as it may be called, to throw the pin f^3 into engagement with the shoulder a^4 , so that at the next operation of the main-punch lever a^2 the gang-punch lever f^2 is also operated, whereby the four punches are moved simultaneously toward the work-support. The operation of the elbow-lever e^2 , however, obviously prevents the complete forward movement of the eyelet-chute, as described in the Glass and Whittemore application above referred to, so that in the opening made by the main punch when the gang-punch is operated therewith no eyelet will be inserted, such condition being desirable in some instances, as above stated. When, however, it is desired to operate the gang-punch without preventing the insertion of an eyelet in the opening simultaneously made by the main punch, the projection e^2 may be disconnected from the cam e^2 by loosening the screw e^2 , which is adapted to draw together the yoke or split collar e^2 to connect the projection e^2 with the cam e^2 . The parts as arranged are therefore easily adapted for the different classes of work above described. It is obviously not essential, however, that there should be any coöperation between the means for preventing the insertion of the eyelet and the means for causing the gang-punch to operate, nor is it necessary that the main-punch lever should constitute the actuating mechanism for the gang-punch. While, therefore, the construction and arrangement shown to illustrate the

invention have many advantages, as has been pointed out, the invention is not limited thereto, since it might easily be embodied in other forms differing specifically from that described.

As has been stated, the spreading of the eyelets at the lower portion of the upper is accomplished in accordance with the present invention by means of an automatic gage for the stock capable of changing its position by a step-by-step movement caused by the co-operation therewith of the other parts of the machine, the said gage being best shown in Figs. 4, 5, and 10. The gage h is herein shown as mounted on and movable with the feed-slide d and consists of a tongue or projection adapted to engage the edge of the stock to determine the position thereof with relation to the devices which operate thereon. To produce an automatic movement of said gage to vary the position of the stock during the feed movement thereof and to consequently vary the position of the eyelets set therein, the said gage is shown as secured to a spindle h^2 , connected with a hub or boss h^2 and having a bearing in an ear or projection d^2 of the feed-slide d and secured by a nut h^2 , so that the said gage h is capable of pivotal movement with relation to said feed-slide to vary the position of the portion thereof which is to engage and position the edge of the stock. The said gage is shown as secured to the spindle h^2 by a set-screw h^2 , whereby means are afforded for adjustment thereof when it is desired to vary its normal position. To control the pivotal movement of said gage to vary its position relative to the feed-plate and the devices which operate upon the stock, the said hub is provided with an arm or projection h^3 , adapted to coöperate with a cam i , the said arm h^3 being shown as having a downward projection or stud h^4 , Fig. 1, in engagement with the edge of the cam-wheel i . The said cam-wheel i is shown as mainly circular and is mounted to rotate upon a spindle i^2 , supported by an arm or projection i^3 from the bracket d^4 , which is provided for the purpose of forming the guide for the supporting-rod d^3 , which carries the upper member of the feeding device, as hereinbefore described.

As shown in Fig. 4, the cam-wheel i is so related to the arm h^3 that when the said arm is engaged or controlled through the medium of the pin h^4 by the main periphery of said cam-wheel the said gage is in its normal position and adapted to position the stock to receive the main line of eyelets where they are not intended to be spread. A portion of the said cam-wheel, however, is, as shown, cut in or depressed at i^4 , it being obvious, therefore, that if the said wheel is rotated in the direction of the arrow, Fig. 4, the pin h^4 will ride down into the depression, allowing the gage h to move to the left, Fig. 4, and correspondingly change the position of the stock relative to that of the devices which operate thereon. The depressed portion i^4

is shown as substantially uniform, so that when the cam-wheel i has turned until the pin h^4 is in the position shown in Fig. 5, or substantially at the middle of the curve i^4 , the gage will be in its extreme left-hand position, and during the continued movement of said cam-wheel will be returned to its normal position, as shown in Fig. 4.

In order that the movement of the gage may 10 be caused by the coöperation therewith of the other instrumentalities to produce a step-by-step change in the position of said gage to determine the position of the eyelets, the spindle i^2 is also provided with a ratchet-wheel i^5 , 15 adapted to coöperate with a pawl k , pivotally connected at k^2 with the main feed-lever D , which swings upon the pivot D^2 to produce the reciprocating feed movement of the slide d . The said pawl is normally held in engagement 20 with the teeth of the ratchet-wheel by means of a spring k^3 and is provided with a handle or extension k^4 , for a purpose to be hereinafter described.

Since the feed-slide d has a straight reciprocatory movement, while the lever D has a swinging movement, it is obvious that at each feed movement of said lever the relation of the ratchet, which is pivoted upon the feed-slide, to the pawl, which is mounted on the 25 said lever D , will be changed, so that during the rearward or inoperative movement of the feed the said pawl will be moved over one tooth of the ratchet and during the forward or operative movement of the feed will engage 30 said tooth to produce a rotation of the said ratchet a predetermined distance, the forward or operative movement being in the direction of the arrows shown on the uppers U , Figs. 4 and 5. When, therefore, the said 35 pawl is in operation during the progress of the machine, there will be a step-by-step feed movement of the cam i , producing a corresponding step-by-step change in the position of the gage between successive feed operations, so that at each succeeding operation of 40 the machine the position of the stock will be changed with relation to that of the devices which operate thereon.

While it is obvious that any desired movement of or changes in the position of the gage 45 may be provided for by properly shaping the cam-surface, the said gage is herein shown as arranged especially for the purpose of spreading the eyelets in shoe-uppers, in which work 50 the said gage should have a certain normal position, which will not vary while the main line of eyelets are being set, and that it should move from this normal position by a substantially uniform movement, receding during the 55 end of the operation on one upper and advancing during the beginning of the operation on the other upper.

In Fig. 4 the gage is shown in its normal position, from which it will move in the step-by-step feed movement above described to 60 the position shown in Fig. 5, reaching this position just prior to the setting of the last eye-

let of the upper shown in Fig. 4, the machine then being stopped with the gage in the proper position to set the first eyelet of the corresponding upper, which, as has been hereinbefore described, must be reversed, as shown in Fig. 5. Referring, therefore, to Fig. 5, it will be seen that in the next feed movement of the machine the ratchet-wheel i^5 will be 70 advanced one tooth, so that the portion i^4 of the cam will engage the projection h^4 and move the gage so as to bring the stock to the proper position to set the next eyelet, and at the next feed movement the said wheel will 75 be advanced another tooth, and so on until the projection h^4 is in contact with the main surface of the cam-wheel i , after which there will be no further movement of the gage, since the remainder of the periphery of the 80 cam-wheel i is uniform.

By properly shaping or proportioning the cam so that in the complete rotation thereof the projection h^4 from the arm h^3 would be reached by the beginning of the depressed 90 portion i^4 of the cam after a certain predetermined number of holes have been punched it is obvious that the operation of the gage might be rendered completely automatic in cases where the machine is intended for certain classes of work wherein the same number 95 of eyelets are to be set at each operation. It is desirable, however, that the gage should operate properly without regard to the number of eyelets which constitute the main line 100 thereof, since the same degree of spread is usually employed in long uppers and short uppers, and means are accordingly provided, as shown herein, whereby the cam-wheel instead of having a continuous step-by-step rotation in one direction is adapted to remain stationary during the operation of setting the main line of eyelets, the feed of the said cam being under the control of the operator, so that he is able to start the operation thereof 105 after the main line of eyelets has been set, thus causing the remaining eyelets to be spread, the gage at the end of this step in the operation being in the position shown in Fig. 5. The feed movement of the gage will be resumed 110 when the next upper is placed in the machine and will continue until the gage has been restored to its normal position, the said gage then being stopped and remaining stationary, the projection h^4 then being in contact with the cam at a point beyond the depressed portion i^4 in the direction of rotation 115 of said cam. To stop or prevent further movement of the cam, as above stated, after it has carried the gage away from and back to its 120 normal position, the ratchet-wheel i^5 is provided with a blank portion i^{50} , which is then in a position to be engaged by the pawl k , which will not, therefore, operate to further 125 advance the said wheel. When, however, the 130 left-hand upper is finished and the right-hand upper has been inserted and operated upon until that portion thereof is reached where it is desired to spread the eyelets, it is obvious

that means must be provided for bringing the cam to the position shown in Fig. 4 either by the complete rotation thereof, a reverse feed movement thereof, or otherwise, this being accomplished, as herein shown, (since, as stated, complete rotation may be undesirable,) by providing the spindle i^2 with a restoring-spring i^{20} , which may be connected at one end to the bracket i^3 and at the other end to the spindle itself, the said spring being shown as a spiral spring surrounding the spindle i^2 and tending to turn the cam i and ratchet i^5 in a direction opposite to that in which it is fed by the pawl k , as above described. In order to prevent the said spring from operating when the pawl k has reached the blank portion i^{50} of the ratchet-wheel i^5 , as above described, a retaining-pawl k^5 is pivoted at k^6 upon the feed-slide d and normally held in engagement with the ratchet-wheel i^5 by means of a spring k^7 . When, therefore, the gage has been moved in the operation of the machine to carry the gage away from and back to its normal position, the cam-wheel i is held in the position which it then assumes by means of the retaining-pawl k^5 against the stress of the spring i^{20} . If, therefore, the said retaining-pawl is thrown out of engagement and the feed-pawl removed from the path of the ratchet, it is obvious that the cam-wheel i will fly back to its normal position, Fig. 4, and will be then acted upon by the feed-pawl k until the blank portion i^{50} reaches said feed-pawl, as above described. To thus disengage the retaining-pawl, a lever or actuating device is conveniently arranged for the attendant, the handle or extension k^4 of the feed-pawl k being herein shown as adapted for the purpose, the said handle being provided with a stop or projection k^{40} , adapted to engage the retaining-pawl k^5 and throw the same out of engagement with the ratchet-wheel, (the feed-pawl itself being also moved out of the path of the ratchet,) so that the cam-wheel i is at once restored to the position shown in Fig. 4, the said position being properly determined by means of the stop i^8 upon the ratchet-wheel i^5 adapted to coöperate with a stationary stop i^{60} upon the supporting-frame.

The return movement of the cam-wheel in response to the stress of its spring will obviously be so rapid as to have practically no effect upon the gage, since the main portion of the said cam-wheel at one side of the depression i^4 therein will be replaced by the corresponding portion thereof at the other side before the gage has moved to any appreciable extent toward the surface i^4 under the stress of its spring i^{20} .

It is not intended to limit the invention to the specific construction herein shown and described, since obvious modifications may be made therein without departing from the invention; nor is it intended to limit the invention to the application of the various features embodying the same to any particular

machine nor to a machine embodying all of said features, since the invention or certain features thereof may obviously be applied to other machines, while the interdependence of the various instrumentalities hereinbefore described, though desirable and useful, is not essential.

I claim—

1. In an eyeleting-machine, the combination with the punch; of the setting devices; a feeding device for moving the stock, after it has been punched, to such a position that the hole made by the punch is presented to the setting devices; a reciprocating feed-chute carrier provided with two or more feed-chutes each adapted to present eyelets to the eyelet-setting devices and each having an independent supply-hopper; means for shifting the position of said feed-chutes with relation to the carrier, whereby any one of said chutes may be adapted to present eyelets to the setting devices and the others rendered inoperative; and connecting mechanism whereby said punch, setting devices, stock-feeding device, and chute-carrier are caused to properly co-operate in the eyeleting operation, substantially as described.

2. In a setting and punching machine, the combination with devices for inserting eyelets or the like; of feed mechanism for the stock, whereby a number of eyelets or the like are consecutively inserted; a supplemental device for punching one or more plain holes in the stock, said supplemental device being normally inoperative; and means for causing the same to operate when desired, substantially as described.

3. In a machine for setting eyelets, rivets, and the like, the combination with the main punch; of the setting devices; means for feeding the stock after it has been punched by said main punch to a position to be acted upon by the setting devices; a supplemental punch or gang of punches normally inoperative; and means for causing said supplemental punch to operate and punch one or more holes in the stock which holes are not subsequently acted on by the setting devices, substantially as described.

4. In a machine for producing a line or series of holes in leather or similar stock, and for inserting in a part only of said holes eyelets, rivets, or the like, the combination with a main punch; of a stock-feeding device; setting devices to operate upon the holes made by said main punch; a supplemental gang-punch for making, at a single operation, a number of holes which are not to be operated upon by the setting devices; operating mechanism for said main punch, stock-feeding device, and setting devices, from which mechanism said gang-punch is normally disconnected, and means for connecting said gang-punch therewith to cause the same to operate, substantially as described.

5. In an eyeleting-machine, the combination with the main punch adapted to punch

holes for the reception of eyelets; of the eyelet-setting devices; means for moving the stock to present the hole made by said main punch to the said eyelet-setting devices; a supplemental punch or gang of punches adapted to punch one or more holes in the stock in which no eyelets are to be set; actuating mechanism for said supplemental punch which is normally disconnected therefrom; and means for connecting said supplemental punch with its actuating mechanism, substantially as described.

6. In an eyeleting-machine, the combination with the main punch adapted to punch holes for the reception of eyelets; of the eyelet-setting devices; means for moving the stock to present the holes made by said main punch to the said eyelet-setting devices; a supplemental punch or gang of punches adapted to punch one or more holes in the stock in which no eyelets are to be set; and common means for connecting said supplemental punch with its actuating mechanism and for preventing the effectual operation of the eyelet-setting devices, substantially as described.

7. In an eyeleting-machine, the combination with the main punch adapted to punch holes for the reception of eyelets; of the eyelet-setting devices; means for moving the stock to present the hole made by said main punch to the said eyelet-setting devices; a supplemental punch or gang of punches adapted to punch one or more holes in the stock in which no eyelets are to be set; and means for connecting together or disconnecting said main and supplemental punches, whereby the latter is rendered operative or inoperative, substantially as described.

8. In an eyeleting-machine, the combination with the main punch adapted to punch holes for the reception of eyelets; of the eyelet-setting devices; means for moving the stock to present the hole made by said main punch to the said eyelet-setting devices; a supplemental punch or gang of punches adapted to punch one or more holes in the stock in which no eyelets are to be set; an actuating-lever for the main punch; and means for connecting the supplemental punch with said lever to cause the same to operate with the main punch, substantially as described.

9. In an eyeleting-machine, the combination with the main-punch lever having a pivotal support upon the frame of the machine, of a supplemental-punch lever also having a pivotal support coaxial with that of the main-punch lever, means for operating the said main-punch lever, and a device for connecting or disconnecting said supplemental-punch lever and said main-punch lever, substantially as described.

10. In an eyeleting-machine, the combination with the main-punch lever having a pivotal support upon the frame of the machine, of the supplemental-punch lever having a pivotal support coaxial with that of the main-punch lever, a movable latch or projection

connected with one of said levers but normally out of the path of the other, and means for moving said projection into the path of the other whereby said levers are adapted to operate simultaneously, substantially as described.

11. In an eyeleting-machine, the combination with the main-punch lever having a pivotal support upon the frame of the machine, of the supplemental-punch lever having a pivotal support coaxial with that of the main-punch lever, a movable latch or projection connected with one of said levers but normally out of the path of the other, and an arm or lever adapted to engage said projection and move it into engagement with the other lever, said arm being adapted to be moved by the attendant, substantially as described.

12. In an eyeleting-machine, the combination with the main punch, of the eyelet-setting devices, means for supplying an eyelet to said eyelet-setting devices at each operation thereof in the normal operation of the machine, a supplemental punch or gang of punches, actuating mechanism for said supplemental punch from which said punch is normally disconnected, and means for simultaneously connecting said supplemental punch with its actuating means, and preventing the eyelet-feeding device from supplying an eyelet to the eyelet-setting devices, substantially as described.

13. In an eyeleting-machine, the combination with the eyelet-setting devices, of a reciprocating eyelet feed-chute provided with an actuating device, a main-punch lever provided with a punch and actuating mechanism, a supplemental lever provided with a punch or gang of punches, said lever being pivoted coaxially with the main lever, a movable latch or projection on one of said levers adapted to coöperate with an engaging portion of the other, and means for moving said latch or projection into the path of said shoulder and simultaneously shifting the point of connection between the eyelet feed-chute and its actuating device whereby said supplemental punch is adapted to operate in conjunction with the main punch and the feed-chute is prevented from presenting an eyelet to the eyelet-setting devices, substantially as described.

14. In a machine for setting eyelets, rivets, and the like, the combination with the consecutively-operating punch and setting devices; of a feeding device adapted after the operation of the punch to engage and hold the stock and to move the same to such a position that the hole made by the punch is presented to the setting devices; a gage for the stock adapted to determine the position thereof prior to its engagement by the feeding device; and means for automatically changing the position of the gage progressively in the operation of the machine to cause the line of work to deviate from a course parallel to the edge of the stock, substantially as described.

15. In a machine for setting eyelets, rivets, and the like, the combination with the consecutively-operating punch and setting devices; of a feeding device adapted after the 5 operation of the punch to engage and hold the stock and to move the same to such a position that the hole made by the punch is presented to the setting devices; a gage for the stock adapted to determine the position thereof 10 of prior to its engagement by the feeding device; a cam coöperating with said gage and adapted by its rotation to progressively shift the position thereof and to thereby cause the line of work to deviate from a course parallel 15 to the edge of the stock; and means for automatically rotating said cam, substantially as described.

16. In a machine for setting eyelets, rivets, and the like, the combination with the consecutively-operating punch and setting devices; of a feeding device adapted after the 20 operation of the punch to engage and hold the stock and to move the same to such a position that the hole made by the punch is presented to the setting devices; a gage for the stock adapted to determine the position thereof prior to its engagement by the feeding device; an automatic device for progressively shifting the position of said gage during 25 the operation of the machine and to thereby cause the line of work to deviate from a course parallel to the edge of the stock; and means for primarily adjusting said gage with relation to said automatic device, substantially as described.

17. In a machine for setting eyelets, rivets, and the like, the combination with the consecutively-operating punch and setting devices; of a feeding device adapted after the 30 operation of the punch to engage and hold the stock and to move the same to such a position that the hole made by the punch is presented to the setting devices; a gage for the stock adapted to determine the position thereof prior to its engagement by the feeding device; and means for automatically shifting the position of the said gage progressively during the movement of the feeding device and to thereby cause the line of work to 35 deviate from a course parallel to the edge of the stock, substantially as described.

18. In a machine for setting eyelets, rivets, and the like, the combination with the punch, of the setting devices, the stock-feeding device for moving said stock from the punch to the setting devices, a gage for the stock mounted on and movable with the said stock-feeding device, and means for shifting the position of the said gage with relation to said 40 feeding device during the movement thereof, substantially as described.

19. The combination with the feed-slide, of the feed-lever for producing a reciprocating movement thereof, a gage for the stock pivotally supported on said feed-slide, a cam rotatably mounted on said lever and adapted 45 to cooperate with said gage to shift the posi-

tion thereof, and means for rotating said cam during the movement of said feed-lever, substantially as described.

20. The combination with the feed-slide, of the feed-lever for producing a reciprocating movement thereof, a gage for the stock pivotally supported on said feed-slide, a cam rotatably mounted on said lever having a double 50 inclined surface, an arm or projection from said gage coöperating with said double inclined surface whereby a movement of said cam in one direction produces a movement of the gage first in one direction and then in 55 the other, and means for actuating said cam, substantially as described.

21. The combination with the feed-slide, of the feed-lever for producing a reciprocating movement thereof, a gage for the stock pivotally supported on said feed-slide, a cam rotatably mounted on said lever, an arm or projection from said gage coöperating with said cam, and means for adjusting said gage with 60 relation to said arm, substantially as described.

22. The combination with the stock-feeding device, of the gage for the stock, a cam coöperating with said gage and adapted by its movement in one direction to produce a movement of the gage first in one direction and then in the other, means for moving said cam step by step during the operation of the feeding device, and independent means for restoring said cam to its normal position, said means 65 being under control of the attendant, substantially as described.

23. The combination with the stock-feeding device, of the gage for the stock, a cam coöperating with said gage and adapted by its movement in one direction to produce a movement of the gage first in one direction and then in the other, means for moving said cam step by step during the operation of the feeding device, a restoring-spring for said cam adapted to be wound during the step-by-step forward movement thereof, and by unwinding to restore the said cam to its normal position, a retaining-pawl for said cam, and means for disconnecting said retaining-pawl to permit 70 the restoring-spring to operate, substantially as described.

24. The combination with the stock-feeding device, of a lever pivotally connected thereto and adapted to produce a reciprocating movement thereof, a cam rotatably mounted on said lever, a gage for the stock pivotally supported upon said feed-slide and having a projection adapted to coöperate with said cam, a ratchet-wheel connected with said cam and adapted by its rotation to produce rotation thereof, and a pawl pivoted on said feed-slide and adapted to coöperate with said ratchet, substantially as described.

25. The combination with the stock-feeding device, of a lever pivotally connected thereto and adapted to produce a reciprocating movement thereof, a cam rotatably mounted on said lever, a gage for the stock pivotally sup-

ported upon said feed-slide and having a projection adapted to coöperate with said cam, a ratchet-wheel connected with said cam and adapted by its rotation to produce a rotation 5 thereof, a pawl pivoted on said feed-slide and adapted to coöperate with said ratchet, a restoring-spring for said cam adapted to be wound during the forward movement thereof and by unwinding to produce a rearward 10 movement thereof, a retaining-pawl in engagement with said ratchet, means for removing the feed and retaining pawls from said ratchet to permit the restoring-spring to operate, and a stop for determining the normal 15 position of said cam, substantially as described.

26. The combination with the gage, of a cam adapted to coöperate therewith to shift the position thereof, a ratchet connected with said

cam to produce rotation thereof, a feed-pawl 20 coöoperating with said ratchet and provided with a handle for moving it out of engagement with said ratchet, a restoring-spring for said cam, a retaining-pawl to prevent the operation of said restoring-spring, and a projection from one of said pawls extending into the path of the other whereby both pawls 25 may be removed from the ratchet to permit the restoring-spring to operate, substantially as described.

In testimony whereof I have signed my name to this specification in the presence of two subscribing witnesses.
